(57) **CLAIM**

The ornamental design for a wax strip, as shown and described.

DESCRIPTION

FIG. 1 is a perspective view of the wax strip of the present invention.

FIG. 2 is a top plan view of the wax strip of the present invention.

FIG. 3 is a bottom plan view of the wax strip of the present invention.

FIG. 4 is a rear elevation of the wax strip of the present invention.

FIG. 5 is a front elevation of the wax strip of the present invention.

FIG. 6 is a right side elevation of the wax strip of the present invention; and,

FIG. 7 is a left side elevation of the wax strip of the present invention.

The broken lines illustrate portions of the wax strip that form no part of the claimed design.

1 Claim, 5 Drawing Sheets(56)
